United States Patent Office

Des. 200,220
Patented Feb. 2, 1965

200,220

CIGARETTE PACKAGE

Bernard J. Tamarin, Whitemarsh, Pa.
(W. Valley Green Road and Hunt Lane, Flourtown, Pa.)

Filed Jan. 10, 1963, Ser. No. 73,132

Term of patent 14 years

(Cl. D58—2)

Fig. 1

Fig. 2

FIG. 1 is a perspective view of a cigarette package showing my new design; and

FIG. 2 is a top plan view thereof.

The drawing is shaded to indicate contrasting colored areas, no particular colors being intended.

The dominant feature of my design resides in the portions shown in full lines.

I claim:

The ornamental design for a cigarette package, substantially as shown and described.
